FILM CARTRIDGE FOR A PHOTOGRAPHIC PROJECTOR

Robert C. Zimmerman, Chicago, Ill., assignor to Bell & Howell Company, Chicago, Ill., a corporation of Illinois

Filed July 24, 1964, Ser. No. 80,994

Term of patent 14 years

(Cl. D61—1)

Fig. 1.

Fig. 2.

FIGURE 1 is a front perspective view of a film cartridge for a photographic projector showing my new design; and

FIGURE 2 is a top rear perspective view thereof. The bottom of the film cartridge is substantially planar and unornamented.

I claim:

The ornamental design for a film cartridge for a photographic projector, as shown and described.
